UNITED STATES PATENT OFFICE.

GEORGE E. WILBUR, OF TAUNTON, MASSACHUSETTS, ASSIGNOR TO THE WEIR STOVE COMPANY, OF SAME PLACE.

DESIGN FOR A COOKING STOVE OR RANGE.

SPECIFICATION forming part of Design No. 23,812, dated November 13, 1894.

Application filed June 22, 1893. Serial No. 478,517. Term of patent 14 years.

To all whom it may concern:

Be it known that I, GEORGE E. WILBUR, a citizen of the United States, residing at Taunton, in the county of Bristol, in the State of Massachusetts, have invented a new and original Design for Cooking Stoves and Ranges, of which the following is a full, clear, and exact description, reference being had to the accompanying drawings, forming a part of this specification, in explaining its nature.

The design relates to six particular features: first, to the legs of the range, each leg having a leaf scroll beginning at the center a and radiating therefrom upon evolute lines; second, to the stove base, which has at the corners a' a scroll of a type similar to that of the legs, and at the center a^2 another scroll of similar pattern, the center and end scrolls being separated by the circular figures a^3 some- what resembling rosettes; third, to the oven door, the corners of which have scroll work similar to that already specified, and which is well shown in the drawing, and which are arranged about the oval bead b , which forms a panel or space for the reception of the name plate.

The fourth feature relates to the name plate, which has the twisted border c oval in shape, scrolls $c' c'$ within the border and above a name space, and an initial space below the name space; surrounded by a scroll having secondary scrolls at each side.

The fifth feature is the design for the ash pit door X , which is well shown in the drawing, and comprises the same idea of scroll lines evolving from the centers of the corners.

The sixth feature is the design for a water heater plate Y , in which the same features again appear as to the corners, and also an additional oval vine-like connection with spirally curved stems extending from each side.

The design is further found in the central panel of the back bracket or plate which supports the elevated shelf, and which at the

bottom represents a spirally wound stem opening upward and into a spread scroll. Each wing of the plate has figures of the same general character as those to which I have already referred, and the upper rosettes and the other special features represented in the drawing.

The salient front corners of the stove top are of a color which contrasts with the color of the edge of the top plate between the corners. This contrast of colors is carried into the oven shelf in the same way, and also into the top shelf and ash-pit shelf. These edges and corners of contrasting colors form a kind of border or frame which emphasizes the shapeliness of the stove as a whole and its outlines, and which contrast with the other design features and add to their effect.

Having thus fully described my invention, I claim and desire to secure by Letters Patent of the United States—

1. In a design for a stove, the design for the stove leg, as herein shown and described.
2. In a design for a stove, the design for the stove base, as herein shown and described.
3. In a design for a stove, the design for the oven door, as herein shown and described.
4. In a design for a stove, the design for a name plate, as herein shown and described.
5. In a stove, the design for the front plate of a water heater, as herein shown and described.
6. In a stove, the design for the central panel of a back plate or bracket, as herein shown and described.
7. In a stove the design for a support for the elevated shelf as herein shown and described.
8. The design for a stove, as herein shown and described.

GEO. E. WILBUR.
